MACHINE FOR CORNER SCARFING OF
BILLETS

Jay P. Van Fossan, Warren, Ohio, assignor to
Republic Steel Corporation, Cleveland, Ohio, a
corporation of New Jersey

Application May 22, 1946, Serial No. 671,644

6 Claims. (Cl. 266—23)

1

The present invention relates generally to the art of shaping and forming metal and more particularly to a novel method of trimming billets and to novel billet trimming apparatus.

Despite the long-existing, insistent demand for greater time and labor-saving economies in billet trimming operations, no method or means satisfactorily meeting this demand has hitherto been evolved.

As a result of my discovery that billet trimming can be accomplished through the employment of heat in a particular manner, I have accomplished billet corner and edge trimming with the apparatus of this invention surprisingly more rapidly and economically than was heretofore possible. Furthermore, the present invention which is predicated upon this discovery has proven an unqualified success in every respect and immediately replaced other billet scarfing means in large scale commercial operations.

Briefly stated, billet scarfing in accordance with this invention is accomplished by applying flame and molten metal to the billet and by moving the flame along the billet and adding molten metal to the billet in the flame as scarfing is accomplished, or by applying molten metal and flame to the same portion of the billet and moving the flame along as scarfing is accomplished.

In accordance with the method of this invention as I have commercially practiced it to commercial advantage, a billet of steel produced in accordance with the customary blooming mill practices and requiring corner and edge trimming was secured in an upright position on edge. Separate flames were then applied to the top and sides of the billet near its upper edges where scarfing was required and, simultaneously, to small steel rods whose ends were close to those surfaces. The steel rods were quickly melted by the flames to the extent that sufficient molten metal was deposited upon the surface of the billet to accomplish local heating and cause flame scarfing to begin. As scarfing proceeded to the desired extent, the flames were moved along the billet at a rate sufficient to effect the desired trimming but not to result in undue loss of the metal of the billet. The rods were moved toward the billet from time to time when molten metal from that source was desired.

It is desirable, of course, that the fused metal be in sufficient quantity, according to its specific heat value and that of the billet, to furnish an adequate supply of heat to the billet to reduce substantially the time required to bring the portion of the billet first to be flame scarfed to

2

scarfing temperature. Generally, I prefer to use metal of substantially the same composition as the billet to minimize specific heat difference, and for the further reason that thereby the possibility of undesirable alloying or chemical action between the molten metal and billet will be minimized or avoided.

For reasons of efficiency and convenience I have carried out this flame scarfing process 10 through the use of a gas flame. Other conveniently applied flames or sources of heat may, however, be used to obtain substantially identical results and such means are contemplated by the appended claims and are within the purview of 15 the present invention.

The apparatus which I have invented is especially suited to this gas flame scarfing because, unlike others, it comprises flame or support members which are capable of conducting 20 and delivering gases to the burner elements.

In the form in which the apparatus of this invention is depicted in the accompanying drawings, it is suited as is no other known apparatus for movement of gas flame producing apparatus 25 along the surface of a metal piece such as a steel billet in accordance with the foregoing description. Referring to these drawings which form a part of this specification:

Fig. 1 is a side elevation view partly in section 30 of one form of apparatus of the present invention situated in operating arrangement upon a billet;

Fig. 2 is a plan view of the apparatus of Fig. 1 with certain parts omitted.

Fig. 3 is a rear end view partly in section of the apparatus of Fig. 1;

Fig. 4 is a front end view partly in section of the apparatus of Fig. 1;

Fig. 5 is a view in elevation and partly in section 40 of a rod carrying assembly of the illustrated apparatus;

Fig. 6 is a side elevation view partly in section of another form of the present invention in operating arrangement on a billet;

Fig. 7 is a plan view of the apparatus of Fig. 6 45 with parts omitted.

Fig. 8 is a rear end view in elevation of the apparatus of Fig. 6.

The apparatus of Figs. 1 to 4 comprises in general a U-shaped frame 1 having supporting wheels 2 carried by wheel yokes 3, and depending arms 4, 5 and 6 having rollers 7 secured thereto near their lower ends. Frame 1 consists of three horizontally disposed U-shaped tubular members 8, 9 and 10, in spaced, nested arrange-

ment, and tie member 11 which extends horizontally between and joins opposed sides of the intermediate member 9 and underlies and provides support to member 10 near its rounded extremity.

Wheels 2, which are to run on the top surface of a billet, are mounted to track and are situated approximately midway between the sides of the U-shaped frame and near the ends of the frame. These wheels, as aforementioned, support the assembly through yokes 3 each of which consists of side or vertical members 13 which are movably secured to the opposed sides of large frame member 8 and horizontally disposed member 14 which extends through the hub of wheel 2 and thus serves as an axle and is suitably secured at each end to members 3 and 13.

A wheel 15 having a threaded hub is screwed on the upper threaded portion of each member 13, the upper extremity of which extends into the opening of a T-fitting 16 secured to the large frame member 8. Two rigid metal ties 17 having openings at their ends through which extend the upper ends of vertical members 13 are gripped at their ends between fittings 16 and the hubs of wheels 15 and extend horizontally across the frame paralleling the axle member 14, tying together members 13 in pairs.

Arm 4, which is suitably connected at its upper end to intermediate frame member 9 at a point about midway between wheels 2, consists of an upper and lower section 4 and 4a; respectively, joined by a block 18 having a threaded transverse opening and being engaged threadwise with rod 19, which is provided with righthand threads at one end. Arms 5 and 6, which are likewise connected to the frame but at points on the opposite side of member 9 from member 4, are joined by horizontally disposed tubes 20 which are threaded into T-fittings 21 on the arms and welded at their other opposed ends to U-shaped clip 22. This clip is engaged for movement with respect to the frame with lefthand threads on rod 19 at its other end. Arms 5 and 6 are disposed substantially parallel to each other but do not parallel arm 4, the lower extremities of arms 5 and 6 being disposed at a greater distance from the lower extremity of arm 4 than the distance separating the upper portion of arms 5 and 6 from arm 4.

Rollers 7 are suitably attached to the lower portions of said arms. In the illustrated apparatus the roller of arm 4 engages the billet at a point approximately midway between and substantially above the points of engagement with the billet of rollers of arms 5 and 6. The frame is thus supported in upright position on the billet and a torque is applied to the billet according to the imbalance of the frame. Also the frame and wheels are guided along the edge of the billet, whether that edge is straight or rather tortuous, so long as the billet sides are substantially parallel at each and every point.

Rod 19 is rotatably carried in a yoke assembly comprising a pair of hangers 24 secured to the frame member 10 by T-fittings 25. The hand wheel 23 is secured to rod 19 between the lower ends of the hangers to enable rotation of the rod by the wheel 15.

An assembly comprising a gas conduit 28, Y-shaped air conduit 29, double valves 30 and single valve 31 in the conduits and small gas conduit 32, which bleeds the conduit 28 before the valve is joined with the frame by couplings 33 which engage the open ends of the tubular frame ele-

ments. Double valve 30 is of sleeve valve construction and is operated by a lever 34 to control the flow of gas and air through the conduits. Single valve 31 is of similar construction and is operated in a similar manner with a similar effect by movement of lever 35. The foregoing valve assembly is inclosed in housing 36. Gas conduit 32 is regulated by adjustable pilot light-screw 37a of the push button lighter 37 situated near the end of that conduit nearest the frame.

Four burners 38 are arranged in pairs on each side of wheels 2 and forward thereof in order that flames generated at the burners may impinge upon the top and sides of the billet and against the rods to be fused. These burners are supplied with gas through four tubes 39 which are joined through valve couplings 40 with flexible hoses 41 which are joined communicatively with the large frame member 8, the gas carrying element of the frame. The burners are supplied with air under pressure through eight tubes 42, which are communicatively joined through valve couplings 43 and hoses 44 with the intermediate and small frame members 9 and 10. Four brackets 45 tie together each of the two air conduits and single gas conduit leading to each burner and, in cooperation with arms 46 depending from T-fittings 47 secured to frame member 9, maintain the burners in fixed relation to the frame.

Two pilot lights 48 situated near the nozzles of each pair of burners are supplied with gas through conduits 49 which are communicatively attached to the gas conduit 32. Each of these pilots is secured in fixed relation to a burner pair by means of a clamp 50 which rigidly ties conduit 49 to a conveniently located conduit communicating with a burner.

Four additional air lines comprising tubes 51 deliver air in the vicinity of the burner flames as desired in accordance with adjustment of valves 52 in these tubes.

Fig. 5 shows one of the rod feeding assemblies which are mounted upon, and supported directly by, the frame element 9. Each assembly includes a bracket 55 carrying blocks 56 in casing 57, lever 58 and a spring mounted rod 59. Each pair of assemblies is mounted on an upright member 60 and is connected to a T-shaped lever 61. The upright members 60 are secured to the frame at opposed points on the sides of frame member 9 through T-shaped fittings 62 which are threaded for engagement with said upright members and are rigidly secured to the frame. The construction of the several assemblies will be clear from the following description of one of them. The lever 58 pivoted at point A, engages spring mounted rod 59 at one end, and engages a notch in lower block 56 in housing 57. Within blocks 56 knife-edged elements 63 are pressed upwardly by springs 64. Rod 59 is pivoted at its upper end to the end of one arm of the T of lever 61. This lever is pivoted at point B where it is connected near the upper end of the upright member 60. Thus rod 59 is movable with respect to the billet upon which the assembly is wheeled and with respect to the assembly by up and down movement of the lever 61 which results in movement of the spring mounted rod 59, lever 58, blocks 56 and knife-edged elements 63, except that the latter elements are movable with respect to the rod only in an upward direction and therefore urge the rod downwardly with each downward stroke of handle 61.

Propelling means 65 comprising a shaft and a

handle is suitably attached as by means of rivets to an under member of the frame such as member 22.

In commercially using the apparatus of this invention as depicted, I dispose arm 4 apart from arms 5 and 6 adequately to accommodate the billet to be scarfed and place the apparatus upon the billet with the wheels 2 in contact with the top surface of the billet. The arms, having been adjusted outwardly preparatory to so mounting the apparatus, are brought closer together by rotating wheel 23 until rollers 7 bear upon the sides of the billet. Using propelling means 65, I then move the apparatus along the billet to bring the burners as close as possible to the portion to be scarfed, and, after suitably adjusting the position of the burners and the rods to be fused to initiate scarfing, I ignite the burners. Adjustment of rods and burners may conveniently be accomplished by rotating one or more of wheels 15 to raise, lower or tilt the frame, thus moving the burners and rods relative to the billet. The rods alone may be adjusted relative to the frame and also relative to the billet by manipulation of the above-described rod mounting assembly which operates to urge the rods downwardly toward the billet when lever 61 is pumped vertically. As scarfing proceeds, I propel the apparatus along the billet until scarfing has been satisfactorily accomplished, whereupon I extinguish the burner flames and remove the apparatus from the billet by reversing the process of adjusting arms 4, 5 and 6 until rollers 7 do not bear against the side of the billet, and by lifting the apparatus from contact through wheels 2 with the billet.

Rods 54 may or may not be adjusted through the operation for fusion by urging them into the flames as fusion occurs and the rods are consumed with resultant formation or deposition of pools of molten rod metal on the surface of the billet. I prefer, however, not to apply molten metal to the billet by fusing these rods after scarfing is begun. In the initial stages of this scarfing operation, as aforementioned, application of molten metal to the billet surface very materially hastens the flame trimming process.

Referring now to another form of apparatus of my invention and to Figs. 6, 7 and 8, it will be observed that the frame of this apparatus is non-tubular and that the stabilizing means are rigidly and unadjustably attached to this frame. Other less apparent differences in the two illustrated forms of this invention in the form and shape and the functions of their parts will be apparent from the below disclosure.

The apparatus of Fig. 6 comprises a frame 66, two frame supporting wheels 67 carried by wheel yokes 68 attached to said frame, arms 69, 70 and 71 depending from the frame and having rollers 72, 73 and 74 secured to their respective lower extremities, and means including conduits, valves and burners for delivering combustible gases and oxygen to a portion of billet surface to be scarfed.

Frame 66 comprises a substantially horizontally disposed rectangular shape 75 made up of four bars 76 welded together. The frame is divided into two substantially square sections by bar 77 which extends between and joins opposite sides of the frame.

Wheels 67, which are to run on the top surface of a billet, are mounted in line to track substantially to one side of the major axis or longitudinal center line of the frame and are situated

approximately beneath the opposite ends of the frame. These wheels support the apparatus through yokes 68 each of which consists of a bar 78, two vertical tubular members 79 which are attached to said bar and immovably fixed with respect to frame, and horizontally disposed tube 80 which extends as an axle through a central opening in one of the wheels and is secured at each end to aforesaid vertical members by means of T fittings 81. Said bars 78 are welded to an end member of the frame.

Arm 69 is welded at its upper end to the edge of the frame, at approximately the midpoint between the ends of that edge, and extends outwardly and downwardly from said edge at an angle of about 120° to the frame. At a point opposite the lower portion of the wheels the arm is bent inwardly so that its lower extremity is approximately perpendicular to the frame. Arms 70 and 71 are likewise connected to the frame but at points along the other edge of the frame and are bound together and braced by stringer 82 opposite ends of which are welded to said arms. The points of engagement of these arms with the frame are approximately equidistant from the midpoint of such edge and are near the ends of that edge. As illustrated these arms extend inwardly and downwardly from the frame at an angle of about 60° thereto to a point opposite the lower portion of the wheels where the arms are bent to define an angle of approximately 90° to the frame. In other words, the arms 70 and 71 are substantially parallel to each other. Arms 70 and 71 are not parallel to the billet sides and arm 69 is not parallel to the billet sides, and the upper ends of arms 70 and 71 are closer to the upper end of arm 69 than the lower ends of arms 70 and 71 are to the lower end of arm 69. A second stringer 83, which has one end welded to arm 69 and the other end welded to the midsection of stringer 82, binds together and braces arms 78 and 71 and arms 69. These stringers are disposed substantially horizontally at a level just above the bottom of the wheels 67 to clear the top of the billet. To the lower section of each of these, three arms rollers are suitably attached.

In the illustrated apparatus the roller of arm 69 engages the billet at a point approximately midway between and substantially above the points of engagement with the billet of rollers of arms 70 and 71. The frame is thus supported in upright position on the billet according to the imbalance of the frame. Also the frame and wheels are guided along the edge of the billet, whether that edge is straight or rather tortuous, so long as the billet sides are substantially parallel at each and every point.

An assembly comprising a gas conduit 84, generally Y-shaped air conduit 85, double valve 86 and single valve 87 is joined with the frame by two metal plates 88 which are welded to an end member of the frame and are bolted to housing 89 of the valves. Double valve 86 is of conventional construction and is adjustable by lever 90 to control the flow of gas and oxygen through the conduits serving aforementioned burners. Single valve 87 is of similar construction and is operated in similar manner and with similar effect, i. e. to control oxygen flow to the burners, by movement of lever 91.

Two burners 92 are arranged on opposite sides of the lead wheel and forward thereof in order that flames generated at the burners may impinge on the top, the sides or the corner of the billet upon which the wheels run, but not upon the

wheels or other parts of the apparatus except the fusible rods hereinafter described. These burners are supplied with cutting oxygen through two tubes 93 and with preheat oxygen through two tubes 94 which are joined through valves 95 and flexible hoses 96 connected to aforementioned conduits and valves. The burners are supplied with natural gas through two tubes 97 which are communicatively joined by valves 98 and flexible hoses 100 to aforementioned conduits and valves. Each of two brackets 101 bind together the two oxygen tubes and single gas tube leading to each burner, adjacent the burner, and in cooperation with one of arms 102 depending from T fittings suitably secured to the frame, maintain the burners in fixed but adjustable relation to the frame.

Two additional oxygen lines 103, each comprising a tube 104 terminating adjacent nozzle of a burner and communicating with header 105 through regulating valve 106, secondary header 107 and flexible hose 103, deliver oxygen to the billet surface as required for scarfing upon suitable adjustment of valves.

Through brackets 108 secured to rigid portions of tubes 93 and 97 the fusible rods and rod holders are secured in adjustable relation to the billet and the apparatus. As shown, there are two fusible rods 109 and rod assemblies carried by the apparatus, and the ends of these rods are disposed close to the ends of the burners so as to be subject to the maximum flame temperature developed in the operation of the burners. There is thus a rod serving each burner. As the rods are consumed in the operation, they may be adjusted downwardly in the rod holder 110 to make more fusible material available to the burners by releasing the pressure retaining the rod in the holders. Said pressure is applied or relieved by movement of screws 111. Actually the rod in this illustration is medium gauge wire stock, but it may be heavier or lighter gauge or of bar stock, and may be of other material than steel or iron, as mentioned above.

The apparatus shown also includes two tubular horizontal members 112 which extend the length of the frame. One of which is secured to the frame through two T fittings 113 which are welded to end members of the frame at points substantially above vertical wheel yoke members 79. The other is similarly attached by T fittings 114 to bars 78 of the wheel yokes at points substantially above the said yoke members 79. Aforementioned arms 102 are secured to the frame through T fittings 115 carried in the forward end of the apparatus by said tubular members 112.

Apparatus propelling means comprising a handle 116 and a shaft 117 integral therewith, is suitably attached to a stringer 83 as indicated in the drawings. The attachment is effected by looping the end of the shaft opposite the handle around said member so that the shaft tightly engages said member, and derives support therefrom.

In the use of the illustrated apparatus, it is suitably set upon a billet of width corresponding to the distance between the bearing surfaces of rollers 72 and 73 and roller 74 so that wheels 57 bear upon the billet and rollers 72, 73 and 74 bear upon the billet and the apparatus is thereby maintained in upright position. Using the propelling means, I then move the apparatus along the billet and bring burners 92 to bear upon the portion of the billet surface to be scarfed. After

suitably adjusting the position of the burners and rods 109 to initiate scarfing, I ignite the burners. The billet surface may be preheated by blowing oxygen upon it before the burners are ignited, and the preheat oxygen system of this assembly is provided for this purpose. As the scarfing proceeds, I propel the apparatus along the billet until scarfing has been satisfactorily accomplished, whereupon I extinguish the burner flames, remove the apparatus from the billet by simply lifting it therefrom.

The rods may or may not be adjusted during the operation. By urging them into the flames as rapidly as fusion occurs and the rods are consumed, pools of molten rod metal are maintained on the surface of the billet. As in the above described use of the apparatus of Fig. 1, however, I prefer to continue rod fusion and deposition of metal on the billet only until scarfing has been satisfactorily begun.

As illustrated in Figs. 3 and 8, the apparatus of this invention is balanced upon a billet as a result of the torque which is applied to the billet through the depending arms and the rollers of the apparatus. In each of these instances the depending arm pair is attached to the heavier side of apparatus and the rollers of these arms contact the billet at points below the point of billet contact of the roller of the single depending arm attached to the other side of the apparatus. It will also be noted that the rollers are each disposed at a small angle to the billet and that the rollers on opposite sides of the billet are pitched oppositely so that the rollers are directed downwardly from the arms toward the billet. Contact of the rollers with the billets, as shown, is along the edge of the rollers and, because of the pitch of the rollers the contact, is limited to a portion of the normal contact surface of each roller.

Although I have referred to air as one of the gases delivered to the burners, in the practice of this invention I prefer to employ oxygen. Other combustion supporting gases may, of course, be employed successfully and their use is contemplated by the appended claims.

As another gas, I have effectively used acetylene but contemplate the employment of natural gas, coke oven gas, propane and the like. Furthermore, I contemplate the use of liquids such as gasoline.

Routine modifications of the herein illustrated apparatus would, of course, be required to adapt it to this liquid fuel operation.

Because acetylene and metallic copper combine to form copper acetylide, a spontaneous explosive, under the conditions obtaining in my apparatus, I employ no copper in parts of my apparatus which would be exposed to acetylene in material amounts and concentrations, such as the conduits, valves and burner elements.

Having thus described my present invention so that others skilled in the art may be able to understand and practice the same, I state that what I desire to secure by Letters Patent is defined in what is claimed.

What is claimed is:

1. A self-supporting billet scarfing device comprising a frame having wheels to run on an edge of a billet, arms depending from said frame and extending downwardly below said wheels and rollers carried rotatably by said arms below said wheels to bear against opposite sides of the billet, and a gas conduit disposed to direct flame upon

the surface of a billet, said frame being disposed substantially to one side of said wheels and said rollers being disposed to bear against the billet at different levels to apply a torque to said billet.

2. A self-supporting billet scarving device comprising a frame having wheels to run on an edge of a billet, arms depending from said frame and extending downwardly below said wheels, and rollers carried rotatably by said arms below said wheels to bear against opposite sides of the billet, and a gas conduit disposed to direct flame upon the surface of a billet, said device having its center of gravity to one side of said wheels, and said rollers being disposed to bear against the billet at different levels to apply a torque to said billet.

3. A self-supporting billet scarving device comprising a frame having wheels to run on an edge of a billet, and a gas conduit disposed to direct flame on the surface of the billet, said frame being offset with respect to the wheels and having an arm depending from one side and two spaced arms depending from the other side, said arms extending downwardly below said wheels, and rollers rotatably carried by said arms below said wheels to engage opposite sides of the billet.

4. A self-supporting billet scarving device comprising a frame having a pair of wheels spaced to run in line on the top of a billet, a pair of arms depending from one side of the frame between said wheels and extending below said wheels, disc-like rollers on said arms below the wheels to bear on one side of said billet in substantial horizontal alignment with each other, another arm depending from the other side of the frame between said wheels and extending below the wheels, a disc-like roller carried by said other arm below the wheels to bear against the other side of the billet between and substantially above the other two rollers, and a gas conduit disposed to direct flame upon a surface of the billet.

5. A self-supporting billet scarving device comprising a frame having a pair of wheels spaced to run in line on the top of a billet, a pair of arms depending from the heavier side of the frame between said wheels and extending below said wheels, disc-like rollers on said arms below the wheels to bear on one side of said billet in substantial horizontal alignment with each other, another arm depending from the other side of the

frame between said wheels and extending below the wheels, a disc-like roller carried by said other arm below the wheels to bear against the other side of the billet between and substantially above the other two rollers, said rollers all being inclined downwardly at a small angle toward the billet, and a gas conduit disposed to direct flame upon a surface of the billet.

6. A self-supporting billet scarving device comprising a frame having a pair of arms depending from one side and another arm depending from its other side, a gas conduit disposed to direct flame on a surface of a billet, and rotatable means for supporting the frame on the billet, said means consisting essentially of a pair of wheels rotatably carried underneath the frame spaced radially to run in line on top of said billet, a pair of disc-like rollers carried by said pair of arms between the wheels and below said wheels to bear on one side of the billet, and another disc-like roller carried by the other arm to bear on the other side of the billet between said pair of rollers and spaced vertically from said roller pair.
